UNITED STATES PATENT OFFICE.

RYUJI SATO AND TANEHISA TANAKA, OF NEW YORK, N. Y.

GARMENT-FASTENER.

1,170,346.

Specification of Letters Patent.

Patented Feb. 1, 1916.

Application filed November 10, 1914. Serial No. 871,363.

To all whom it may concern:

Be it known that we, RYUJI SATO and TANEHISA TANAKA, subjects of the Emperor of Japan, residing at New York, in the county of New York and State of New York, have invented new and useful Improvements in Garment-Fasteners, of which the following is a specification.

This invention relates to garment fasteners and it consists in the novel features hereinafter described and claimed.

An object of the invention is to provide a fastener of simple and durable structure which may be easily and quickly manipulated for the purpose of connecting together the adjacent edge portions of a garment or article of apparel.

The parts of the fastener are so arranged as to effectually hold or secure the edge portions of the garment and the parts are also susceptible of easy and quick manipulation for the purpose of disconnecting the adjacent portions of the garment.

With the above object in view the fastener comprises a flexible member having in the vicinity of its opposite edges rows of members having guideways provided at the inner ends thereof. The terminal members at one end of the rows have the guideways closed at one end and the terminal members at the opposite end of the rows constitute securing devices and are devoid of the said guideways. Stud members are mounted upon the edge portions of the garment or article of apparel and are adapted to move in the guideways. The said studs are also arranged in rows and the terminal studs at one end of the rows are in the form of securing devices adapted to coöperate with the securing devices hereinbefore mentioned whereby the parts are effectually held together while the said securing devices are in engagement.

In the accompanying drawing:—Figure 1 is a plan view of the edge portions of an article of apparel having the studs applied thereto and showing the flexible member partly in perspective with the guide members mounted thereon. Fig. 2 is a transverse sectional view in detail on the line 2—2 of Fig. 1. Fig. 3 is a under-plan view of the guide members.

As illustrated in the accompanying drawing the garment is indicated at 1 and as shown in Fig. 1 of the drawing studs 2 are mounted in the vicinity of the edge of the

garment. The said studs are arranged in rows and the terminal stud 3 of the row is in the form of a stud usually employed as one of the members of a glove fastener. The 60 studs other than the stud 3 are all alike and a description of one will suffice. Each stud 2 comprises a head 4 and a shank 5. In the form of stud as shown in Fig. 2 the head 4 and shank 5 are integral and are formed from a single piece of sheet metal. The end of the shank 5 is spread as at 6 and is secured against the side of the garment 1. A plate 7 is mounted upon the shank 5 adjacent the head 4 and bears against the opposite side of the garment 1.

The fastener also includes a flexible strip or body 8 having mounted thereon in rows guide members 9. The terminal units 10 of the guide members 9 are of the usual socket 75 form of glove fastener devices and are adapted to coöperate with the studs 3 for securing the strip 8 with relation to the end portions of the garment 1. The guide members 9 consist of head portions 11 and shank 80 portions 12 the said shank portions passing through the strip 8 as best shown in Fig. 2 of the drawing. The head portions 8 may be plain or ornamented as desired and the said head portions lie beyond the outer side 85 of the strip 8. Guide plates 13 are mounted at the inner ends of the shanks 12 and are located at the inner side of the strip 8. The plates 13 are provided with spaced guide flanges 14. As indicated in Fig. 1 of the 90 drawing the space between the adjacent edges of the guide flanges 14 upon the terminal guide member 9 is closed by an additional flange 15 the object of which will be described hereinafter.

Therefore it will be seen that simple and efficient securing devices are provided for connecting the edge portions of a flexible strip with the edge portions of a garment and that the parts may be easily and quickly manipulated when being connected together or detached from each other.

Having described the invention what is claimed is:—

1. A fastener comprising a member having spaced guide flanges, a stud having a head of greater diameter than the space between the flanges and a shank less in diameter than the space between the flanges, said stud adapted to be received between the 105 flanges, and a flange plate standing out from the shank and spaced from the head of the 110

stud and bearing against the head and shank at their point of juncture.

2. A fastener comprising a member having spaced guide flanges, a stud having a head of greater diameter than the space between the flanges and a shank less in diameter than the space between the flanges, said stud being adapted to be received between the flanges and a flange plate having an opening which snugly receives the shank,

the edge of which bears against the head, said flange plate being spaced from the head of the stud.

In testimony whereof we affix our signatures in presence of two witnesses.

RYUJI SATO.
TANEHISA TANAKA.
